UNITED STATES PATENT OFFICE.

ALBERT O. ROOD, OF NEW YORK, N. Y., ASSIGNOR TO VINCENT P. TRAVERS,
OF SAME PLACE.

ART OF MAKING HAMMOCKS.

SPECIFICATION forming part of Letters Patent No. 296,460, dated April 8, 1884.

Application filed November 17, 1883. (No model.)

To all whom it may concern:

Be it known that I, ALBERT O. Rood, a resident of New York city, in the county and State of New York, have invented an Improvement in the Art of Making Hammocks, of which the following is a full, clear, and exact description, reference being made to the accompanying drawings, in which—

Figure 1 is a plan view of finished hammock-body and a partly-finished hammock end, showing it on the machine. Fig. 2 is a vertical longitudinal section of the machine on which a hammock formed in accordance with my mode may be made, showing a hammock on it in process of having one of its ends finished. Fig. 3 is a top view of a hammock having one of its ends finished and the other in process of construction. Figs. 4, 5, and 6 are diagrams showing different stages of progress in the manufacture of the hammock ends.

This invention has for its object to simplify the mode of constructing hammocks, and particularly the ends thereof, which are the parts of hammocks containing the converging threads and the suspension eyes or loops.

The invention consists, principally, in forming the hammock-body with loops in the ends thereof in any known manner; in then forming each end of the hammock by drawing a cord, from which the converging strands are to be made, through the loops at the ends of the hammock-body in a straight line, and in then drawing this thread from between said loops, forming of it the converging strands of the hammock end, and finally uniting these strands into a terminal eye, all as hereinafter more fully described and claimed.

In the accompanying drawings, the letter A represents a suitable table, which should be a little longer than the full length of the hammock to be made thereon, at least not shorter, and which in its supporting-frame B has bearings for supporting the reels C C, which reels 45 contain the cord or thread that is to be worked into the hammock ends. The hammock-body D is placed on this table A, and when the first end of the hammock is to be attached to the body D—as, for instance, is indicated in 50 Fig. 1—the end of the body which is for the time being not to be joined to the hammock

end has drawn through it a stick or bar, E², which rests against pins a a, that project from the face of the table A, as shown. By this bar E² and pins or projections a, I am enabled 55 to draw the hammock end, which is to be formed at the other end of the body D, properly taut. In now making the hammock end I take a single or double strand (see Figs. 4 and 6) from the reel C beneath and 60 pass it in a straight line through the little end loops b that are formed on the hammock-body D, and then fasten the free end of the thread or cord E to a pin, d, which projects from the table A. This is clearly shown in 65 Fig. 4. I now insert the finger or any other instrument between the end loops b b that are nearest the tied end of the cord E, (in Fig. 4 I have marked these end loops 1 and 2,) and, 70 taking hold of the cord between these loops, 75 draw it into a loop of sufficient length to permit me to place it over the pin d and over another pin, e, which projects from the table A in line transversely with the pin d. The lines of cord which are marked f g in Fig. 6 show 80 how the part of the cord E which was thus withdrawn from between the little end loops 1 and 2 is laid around the pins d e. It will be seen from this figure that the two lines of strand which are thus drawn from between the 85 loops 1 and 2 are crossed before they are slipped over the pins d e—that is to say, the strand f, which was nearest pin d, is carried to pin e, and the strand g is carried to d. This is the preferable arrangement. In Fig. 5, which 90 differs from Fig. 6 simply in showing the cord E to be doubled instead of single, the lines f and g are also clearly shown. After the first layer of cord around the pins d e has been located the finger is inserted between the end 95 loops 2 and 3 and another part of the cord E drawn out, as clearly appears from Fig. 6, which part is drawn to a sufficient extent to allow it to be laid over the pins d e after being first twisted or crossed, as in Fig. 6, and so on, until a loop formed by drawing the cord E from between every two little loops b has been laid around the pins d e, as is indicated on the left-hand end of Fig. 3 and on the right-hand end of Fig. 1. It is clear that the 100 cord E, as it is being drawn over the pins d e, is uncoiled from the reel C. When the first

end of the hammock has been completed to the extent stated, (see Fig. 1,) the end of the cord E is cut off the reel, as at h in Fig. 1, and tied to the first end that was tied to the pin d. 5 Now that much of the hammock end that extends between the pins d e in a straight line is wound by coiling around it a thread or cord of suitable thickness. This wound portion will be just long enough to make from it the end 10 eye, i, of the hammock, (see Fig. 3,) the pins d e being spaced with that object in view. When this winding has been completed, the hammock end is slipped off the pins d e, or these pins are withdrawn, and a single pin, j, 15 is inserted in a hole formed for its reception near the end of the table A and through the wound part of the hammock end, which is then closed around said pin by further winding of a thread to complete the formation of 20 the eye i, as indicated in Fig. 3. When one end of the hammock has been thus entirely completed, the rod E² is withdrawn and the other end formed of a cord or thread, in the same manner as has been described with reference to the first end. 25

I have found that by drawing the cord in a straight line through the end loops b b, and then gathering it up to form of it the converging threads of the hammock end, much loss of 30 time which at present is occasioned in the manufacture of hammock-ends is avoided and fully as good results are obtained.

Instead of hanging two reels on or near the table A, one reel alone may be used, as the

thread E can be taken therefrom for forming 35 first one and then the other end of the hammock.

I claim as my invention—

1. The art of making hammocks which consists in forming the hammock-body with loops b b in the ends thereof in any known manner, then forming each end of the hammock by drawing the cord E, from which the hammock end is to be made, in a straight line through the end loops b b of the hammock-body, and 40 in then drawing said cord from between said end loops b b, forming of it the converging strands of the hammock end and in finally 45 uniting these strands into a terminal eye, i, substantially as herein shown and described. 50

2. The art of making hammocks which consists in forming the hammock-body with loops b b in the ends thereof in any known manner, then forming each end of the hammock by drawing the cord E in a straight line through 55 the loops b b that are at the ends of the hammock-body D, in then drawing this cord out from between the end loops b and holding it temporarily, in then coiling or winding the outer part of this cord, and in then forming 60 from this coiled or wound portion the eye i at the end of the hammock, substantially as herein shown and described.

ALBERT O. ROOD.
